UNITED STATES PATENT OFFICE.

CHRISTIAN HEUMADER, OF ST. JOSEPH, MISSOURI.

SHIRT-TRUNK.

SPECIFICATION forming part of Letters Patent No. 651,758, dated June 12, 1900.

Application filed March 15, 1900. Serial No. 8,764. (No model.)

To all whom it may concern:

Be it known that I, CHRISTIAN HEUMADER, a citizen of the United States, residing at St. Joseph, in the county of Buchanan and State 5 of Missouri, have invented certain new and useful Improvements in Shirt-Trunks; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

15 My invention relates to trunks, and more especially to that class of trunks used by drummers or traveling salesmen for their goods.

The objects of my improvements are, first, 20 to provide a shirt-trunk in which a large number of shirts may be frequently shipped, handled, and displayed without injury to said shirts; second, to so construct and arrange the parts of a shirt-trunk that any desired 25 style of shirt may readily be extracted or taken therefrom without removing or disturbing other trays than the one desired; third, to so construct a shirt-trunk that each and every tray may be conveniently and 30 quickly arranged in a suitable position for displaying all the shirts in said trays; fourth, to so construct a shirt-trunk that the trays will all be held securely therein, so as to avoid rocking and rubbing of one tray against 35 another, and thus avoid consequent wear and injury of trays arising from agitation while shipping; and, fifth, to construct a shirt-trunk which shall be cheap in cost of manufacture, extremely light of weight, durable, and of 40 comparatively small dimensions when the number of shirts contained therein is taken into consideration. I attain these objects by the mechanism illustrated in the accompanying drawings, in which—

45 Figure 1 is a perspective view of a trunk open. Fig. 2 is a transverse section of the trunk-body cut vertically. Fig. 3 is a transverse section of a closed tray. Fig. 4 shows a transverse section of tray held in alinement 50 for leaning against a wall or other support.

One of the essential features of my invention consists of a certain number of suitably-

constructed trays and of a trunk-body especially designed for the reception of a certain number of said trays.

55 Another feature is in the construction of the trays whereby each tray may be suitably arranged and constructed for the reception of any desired number of shirts and the trunk-body may be suitably proportioned to receive 60 any desired given number of trays.

The trays 1 and 2 are constructed in any substantial manner known to the trunk-maker's art, but are preferably constructed of strips of wood, which form the frame or skeleton thereof, and bound and backed with ducking or canvas and reinforced with strips of fiber. The body 3 of the trunk may likewise be constructed in various proportions and in any one of the various styles now known to trunk-makers; but said trays 1 and 2 are hinged together at 4 and are adapted to be placed in position and to hold shirts, as shown and hereinafter more fully described. Said trunk-body must be of proper width and of correct 75 length to be suited to receive a certain number of trays and be suitably arranged to rigidly hold said trays in place therein, as hereinafter described.

In the use of my invention a shirt 5 is 80 placed in one of the compartments 6 and ordinary tapes 7 are suitably attached to end piece 8, and after passing through apertures 9 have their free ends 10 brought back through notches or slits 11 and secured in suitable fasteners 12, thus securing the shirt 5 in place in tray 2, with the collar 13 in position, as seen in Figs. 1 and 3. Shirt 14 is secured in the same manner as above described in tray 1, but with its collar 15 in position as seen in 85 Figs. 1 and 2, thus bringing the collars 13 and 15 in opposite ends of one compartment 6, where trays 1 and 2 are closed together, as seen in Fig. 3, thus economizing space and avoiding injury of one shirt 5 by the rubbing 90 of shirt 14, and vice versa.

I am aware that shirts have been held in place by elastic tapes and also by spring-clips; but the former allows motion and consequent rubbing and abrasion, while the 100 spring-clip cuts and tears the parts of a shirt to which it is attached; but I am not aware that common tape, which may readily be loosened from a suitable fastener, allowing

ready insertion and removal of shirts and of handling and shipping without injury to said shirts, has been used.

Tray 2 is supported in position at an angle, as seen in Fig. 1, by means of the double-tape brace 16, which is suitably attached at its upper end to partition 17 and at its lower end to partition 18 by crossing through aperture 19 and being passed as a loop into notch 20 or slit 20 in partition 18, which arrangement allows the loop of tape 16 to be easily removed from the notch 20, after which the brace-tape 16, being thus liberated or loosened at its lower end, allows trays 2 and 1 to be placed in position, as seen in Fig. 4, and to be held in alinement by the application of a suitable clamp 21, (preferably made of fiber,) as seen in Fig. 4, in which position the described trays 2 and 1 are seen supported in their leaning position against an ordinary wall 22, or they may be placed in a horizontal position, (not shown,) as on a table or floor.

My invention is especially designed to furnish every facility for rapidity in the placing of the trays 2 and 1 in the trunk-body 3, as with the class of people (traveling salesmen) who will use said trunk speed in handling is of vital importance. Trays 2 and 1 may be hastily forced into position seen in Fig. 3 without touching or taking hold of or removing clamps 21, since 21 is made, preferably, of fiber, which is elastic to a certain extent and will of itself spring from its position seen in Fig. 4 and will gravitate into tray 1 when trays 2 and 1 are forced into position seen in Fig. 3, and being attached to the free end of tape 16 cannot be lost or mislaid. When in position and folded, the studs or posts 31 will keep the free edges of trays 2 and 1 in register with each other. After trays 2 and 1 are in the position shown in Fig. 3 they may be quickly held in a vertical position and placed in trunk-body 3 (see Fig. 2) and in their descent into said body will be guided into place by the sloping longitudinal cleats 23 and 24 until said trays rest upon cleats 25, after which the lid 26, rotated upon hinges 27 from position seen in Fig. 1 to position seen in Fig. 2, carry elastic or yielding strips 28 and 29 downward and onto trays 2 and 1, holding them securely in the position seen in Fig. 2, preventing rubbing of trays and consequent injury thereto. Suitable labels 30 will enable the operator or user of my invention to ascertain which tray or trays to remove, as he desires, one pair being thus removed, as seen in Fig. 1.

Having fully described my invention, what I claim as new, and desire to secure by Letters Patent, is—

1. In a shirt-trunk, the combination with two tray-sections hinged together at one edge

and provided with partitions, one of the partitions being provided with a notch extending toward the hinged edge of the section, of 65 a brace permanently secured to one of the partitions of the other section at one end and adapted to enter the notch of said partition with the other end, the length of the brace being less than the distance from the point 70 of permanent attachment to the bottom of the notch when the sections are in alinement with each other.

2. In a shirt-trunk, the combination, with two tray-sections hinged together at one edge, 75 of a notched flexible clamp adapted to fit over the hinged edges of the sections and normally hold the sections in alinement but adapted to be automatically removed therefrom when the sections are forcibly swung upon their 80 hinges.

3. In a shirt-trunk, the combination, with two tray-sections hinged together at one edge and provided with partitions, one of the partitions being provided with a notch extending 85 toward the hinged edge of the section, of a brace permanently secured to one of the partitions of the other section, the free end of which is adapted to enter the notch of said partition, and a notched flexible clamp secured to the free end of the brace in position 90 to be placed upon the hinged edges of the sections and to be automatically removed therefrom.

4. In a shirt-trunk, the combination, with tray-sections hinged together at one edge and provided with apertured partitions, of a fastener at one end of the section, a tape secured to the opposite end having its intermediate portion passed through the partitions and its 100 free end detachably secured to the fastener.

5. In a shirt-trunk, the combination, with tray-sections hinged together at one edge, of labels on one end thereof, said trays being of 105 a greater length than the depth of the trunk and arranged transversely therein with the labeled ends extending above the top of the trunk-body.

6. In a shirt-trunk, the combination, with the body, of yielding strips secured longitudinally upon the front and upon the top and bottom, the strips on the front being beveled on top, of a series of hinged tray-sections 110 therein, each of a greater length than the depth of the trunk-body and arranged transversely thereof, the front edges engaging with the strips on the front and the ends with the strips on the top and bottom.

In testimony whereof I affix my signature in presence of two witnesses.

CHRISTIAN HEUMADER.
